CLAIM

The ornamental design for a switching device for producing, distributing or transforming electricity, as shown and described.

DESCRIPTION

FIG. 1 is a front elevation view of a switching device for producing, distributing and transforming electricity showing our new design;

FIG. 2 is a rear elevation view thereof;

FIG. 3 is a top elevation view thereof;

FIG. 4 is a bottom elevation view thereof;

FIG. 5 is a left side elevation view thereof;

FIG. 6 is a right side elevation view thereof; and,

FIG. 7 is a front left side perspective view thereof.

The broken line portion of the figure drawings is included to show portions of the article that form no part of the claimed design.
